CLAIM

The ornamental design for a lounge chair, as shown and described.

DESCRIPTION

FIG. 1 is a perspective view of a lounge chair showing our new design;

FIG. 2 is a front elevational view thereof;

FIG. 3 is a rear elevational view thereof;

FIG. 4 is a right side elevational view thereof, the left side being a mirror image thereof;

FIG. 5 is a top plan view thereof;

FIG. 6 is a bottom plan view thereof;

FIG. 7 is a perspective view of a second embodiment of our new design including a tablet arm; and,

FIG. 8 is a perspective view of a third embodiment of our design.

The fragmented cross hatching is understood to represent fabric and would be continuous throughout the circumscribed areas. The chair shown in FIG. 7 is like that shown in FIGS. 1-6 with the exception of the tablet arm. The chair shown in FIG. 8 is like that shown in FIGS. 1-6 with the exception of the wheel members. Any portions of FIGS. 7 and 8 which have not been shown or described form no part of the claimed design.
